UNITED STATES PATENT OFFICE.

SEBASTIAN ZIANI DE FERRANTI, OF HAMPSTEAD, LONDON, ENGLAND.

PROPELLION APPARATUS FOR SHIPS, BOATS, AND THE LIKE.

996,324.

Specification of Letters Patent. Patented June 27, 1911.

Application filed April 17, 1905. Serial No. 256,108.

To all whom it may concern:

Be it known that I, SEBASTIAN ZIANI DE FERRANTI, a subject of the King of Great Britain and Ireland, residing at 31 Lyndhurst road, Hampstead, London, N. W., England, have invented new and useful Improvements in and Relating to Propulsion Apparatus for Ships, Boats, and the Like, of which the following is a specification.

10 My invention relates to propulsion apparatus for ships, boats and the like and has for its object to provide an improved plant in which the motive power is developed in an internal combustion turbine adapted to 15 work with maximum efficiency and economy under various conditions of speed.

My invention consists in a propulsive installation for ships, boats and the like in which the screw or screws, paddles or the like are actuated by one or more internal combustion turbines having means for varying the effective action of the working fluid on the blades, according to the power required.

25 My invention also consists in the improved apparatus and the details thereof to be hereinafter described.

To satisfy the requirements of marine propulsion, the turbines must be capable of 30 running in either direction. They must also be capable of giving at maximum economy the correct torque in proportion to the liquid resistance of the vessel at any pre-determined speeds. For example at full speed 35 the turbine will be required to give the full amount of torque; at .8 of the full speed it will be required to give .55 of the full torque, and at .6 of the full speed, which is the speed commonly adopted for cruising, 40 it will be required to give .2 of the full speed torque. It is thus evident that whereas as the speed is only varied in a small proportion, the torque required has an immense variation. According to my invention I 45 provide means whereby these variations of speed and corresponding variations of torque may be obtained simply and with the maximum economy. It is generally sufficient that for marine propulsion only one economical 50 speed astern should be provided for, the amount of the torque at this speed being regulated by hand and the turbine working efficiently at only one point of speed reversing.

My invention also provides for this case being fully met. It is also necessary that 55 the speed of the screws should be reduced to as nearly as possible correspond with the speeds of the present fast running reciprocating engines. According to my invention, this is most nearly approached to. 60

Referring now to the accompanying drawings which illustrate my invention and form part of my specification, Figure 1 shows a diagrammatic view of an installation constructed according to my invention. Figs. 65 2 and 3 show forms of control mechanisms for turbines employing as the working fluid steam or air heated by the internal combustion of a suitable fuel. Fig. 4 shows a form of turbine with blades sufficiently long to 70 allow passages of the fluid through them at different radii. Fig. 5 shows a form in which successive passes of the fluid through the blades takes place at the same radii. Fig. 6 shows a form of reversing turbine in 75 which the blades are three times the radial depth required for a single pass. Figs. 7 and 8 show elevation and plan of a form of reversing turbine in which the blades are twice the radial depth required for a single 80 pass. Fig. 9 shows a turbine having double length blades disposed parallel to the axis of rotation. Fig. 10 shows a form of turbine in which oppositely running wheels are used, each wheel having multiple rings of radially 85 disposed blades. Fig. 11 is a diagram of a turbine divided into segments for purposes of regulation. Figs. 12, 13 and 14 show details of the different segments as applied to a non-reversing single wheel return guide 90 type of turbine. Fig. 15 is a diagram of a reversing turbine adapted for marine propulsion. Figs. 15^a, 15^b, 15^c, and 15^d, are detail views of the different segments of the arrangement shown in Fig. 15. Figs. 16 95 and 17 show a form of automatic return guide in working and non-working position respectively. Fig. 18 shows a form of combustion chamber having water jacketed multiple nozzles. Fig. 19 shows another form 100 in which a long tube is arranged to prevent back ignition. Fig. 20 shows a method of applying turbines to the propulsion of paddle wheel steamers. Fig. 21 being a modification of the arrangement shown in Fig. 20. 105 Fig. 22 is a section on the line C—D on Fig.

21 showing the idler wheel and brake mechanism.

I wish it to be understood that the drawings are of a diagrammatic nature, and where desirable similar elements in the different drawings are denoted by the same reference letters.

In carrying my invention into effect and as applied by way of example to a plant 10 having opposite handed propellers on concentrically disposed shafts I provide a turbine having oppositely running wheels, *v*, and *w*, Fig. 1, which are operated by the high temperature working fluid issuing from 15 the combustion chambers, *a*, through expanding nozzles, *b*, so as to reduce the high temperature of the working fluid to such a degree as the materials of construction can 20 safely withstand. The wheels, *v*, and *w*, actuate opposite handed propellers, 6 and 7, through concentrically arranged shafts, 8 and 9, and are provided with two concentric rings of blades which are disposed in opposite directions in each ring for purposes of 25 reversing, separate sets of nozzles and combustion chambers coacting with each ring of blades being disposed in convenient positions around the turbine casing. The turbine is arranged to give the correct torque 30 in relation to the speed by any of the methods to be hereinafter described. The fuel and air are introduced into the combustion chamber, *a*, from any suitable sources through the pipes, *h* and *m*, by mechanism 35 which I will hereafter describe with reference to Figs. 2 and 3 the air in this case being compressed by separately driven compressors, *h'*. A pipe, *c*, leads steam which is preferably superheated while passing 40 through the jacket, *e*, before entering the combustion chamber, *a*.

The high temperature gases from the combustion chamber, *a*, after operating on the turbine wheels are led through regenerators, 45 10, of any suitable type where the balance of the available heat is utilized to heat the feed water which enters the regenerator by the pipe, 11, and is conducted to the boiler by the pipe, 12.

50 In some cases air may be utilized to form the working fluid which then becomes of a noncondensable nature thereby rendering the boiler or evaporator unnecessary in which case the regenerators may then be used to im- 55 part heat to the air before it enters the combustion chambers. Again in other cases the working fluid may be partly of a condensable nature as for example in the case where it consists of a mixture of the products of combustion and steam; the regenerator may in these circumstances be used either to partially or totally evaporate the condensable part of the working fluid. When only partial evaporation of the working fluid takes 60 place in the regenerator, the pressure at which

the regenerator works should preferably be such that the unevaporated portion will immediately "flash" into steam on its introduction into the combustion chambers, so that no further evaporating plant will be 70 necessary.

What I consider as essential to my invention is that the nature or condition of the working fluid should be such as to preclude the possibility of any material deposit of 75 moisture on its passage through the turbine as otherwise skin friction and eddy losses will be incurred which will materially affect the efficiency of the plant. Such losses are avoided by using air, or steam superheated, by internal combustion, or a mixture of steam and products of combustion as hereinbefore described. The pressure energy of the working fluid is converted into velocity 80 energy as it issues from the combustion chambers in expansion nozzles which reduce the temperature of the working fluid to such a degree as not to act detrimentally on the constructive materials employed.

85 I will now describe some of the details of the arrangement shown in Fig. 1. Thus referring to Fig. 2, an arrangement of parts is shown suitable for use with a steam turbine, the steam being highly superheated by burning in it some suitable fuel. In the figure, the combustion chamber is shown at *a*, the nozzle, *b*, issuing direct therefrom. (It should be noted that these nozzles are not shown in their true shape in Figs. 2 and 3 owing to the manner in which the sectional plan cuts them, rendering them considerably fore-shortened). Steam is admitted by way of the pipe, *c*, and valve, *d*, into the jacket, *e*, surrounding the combustion chamber whence it passes through suitable openings into the interior of the chamber, as indicated by the arrows. Inside the combustion chamber is a flame tube, *f*, into which air is admitted from the main air supply pipe, *h*, by way of any suitable valve, *i*, while oil or gas is likewise admitted by way of a valve, *k*, from the main fuel supply pipe, *m*. I preferably place the igniter, *n*, which may be of any suitable type, in a subsidiary or firing tube, *o*, which is supplied by branches from the main air and fuel supply pipes, *h* and *m*, above mentioned, these branches being controlled respectively by valves, *r* and *s*. The various steam, air and fuel valves above mentioned I control by means of cams, eccentrics or the like such as *t*, mounted on a common shaft, *u*. The electric igniter, *n*, is indicated as operated by the rod, or the like working the auxiliary air valve, *r*. The eccentrics, *t*, are set on the shaft, *u*, at suitable angles to cause the various valves to operate in any desirable sequence, a typical cycle of operations being as follows:—First, air and fuel are admitted to the firing chamber, *o*, by way respec-

tively of the valves, *r*, and *s*. The electric igniter, *n*, is then brought into play the mixture ignites and a flame is projected into the flame tube, *f*. The air and fuel admitted 5 into this tube through the valves, *i* and *k*, will then be fired, the final action of the mechanism being to cut off the igniter and the gas and oil to the firing chamber, and thus removing the point of maximum tem- 10 perature from the igniter.

In Fig. 3 a modification of the arrangement just described is shown applied to the case of a turbine employing air in which a suitable fuel is burned as the working 15 medium. The same reference letters are used as in Fig. 1 to denote corresponding parts. It will be seen that in this modification, a separate eccentric is shown to operate the igniter, *n*, while the flame tube, 20 *f*, is dispensed with, the main air supply entering the combustion chamber, *a*, by way of the jacket, *e*, while the fuel is introduced directly into the same chamber preferably at the end remote from the nozzle, *b*.

In some cases a single combustion chamber may be used with one or more nozzles issuing therefrom, or several chambers may be used. Where I use a single chamber, I supply this intermittently with the elements 30 used to form the working fluid. The length of time for which these elements are supplied determine the power given off. For this purpose the admission valves must be large and work with a quick motion, so as 35 to give clean opening and closing. An electric igniter may be used which is worked either continuously or intermittently, or a firing tube such as already described may be used; but in this case I may sometimes use a 40 firing tube worked continuously, care being taken that the electric igniter is of such a form and so placed as to receive the minimum injury from the heat of the burning gases.

As it is very desirable when employing a 45 number of combustion chambers that the duration of operation of the individual chambers should be as long as possible, and as this is inconsistent with the obtaining of a constant torque, I prefer to have several 50 intermittently acting chambers, the governing being obtained by regulating the length of time during which these chambers are in operation. In order to obtain good turning, 55 I work these chambers consecutively and at equal intervals of time. The periods may then be quite long, and the turning still very good. It is of course clear that the chambers when so worked must be operated as 60 already described; viz., by the approximately simultaneous admission and stoppage of all the elements necessary to form the working fluid.

In carrying out my invention, I use where 65 possible a compressor of the rotary type,

using liquid as the medium of compression, but with certain modifications in order to suit the new conditions. It is necessary to provide for separate driving of this compressor as shown in Fig. 1, as in most cases 70 this is necessitated by the varying speeds and reversing of the main turbines. As the compressing plant will run at approximately constant speed, I regulate the amount of air in some cases by means of bringing into 75 operation a greater or less number of such compressors feeding in parallel. I provide suitable non-return valves, and suitable control valves for stopping of the water supply with the minimum shock, an air buffer or 80 cylinder being provided to facilitate the accomplishing of this result, the compressor moving part running dry when cut out of operation by means of the above valves. I may however, according to another method, 85 govern the amount of compressed air supplied by means of working one or more compressors intermittently at slow periods, and varying the length of the periods for purposes of regulation. Where two or more 90 compressors are worked in this way, I make their periods follow each other consecutively, so as to give the greatest evenness of pressure and absorption of work from the driving turbines. I may feed the compressor 95 with air in comparatively short blasts, or in the case of the compressors using water, I may feed the water at intervals of greater or shorter length, so that the compressor works intermittently. It is therefore compressing at one time and then rotating light without doing any external work. By this means compressors of the full capacity necessary may be worked to better advantage on 100 low loads than would otherwise be the case. It is of course necessary to have a suitable amount of air storage in either of the above arrangements.

I effect the intermittent action of the compressor by means of automatic gear worked 110 from the turbine or compressor shaft or any other source of power. The valves are so arranged as to cut the compressor out of action periodically, and the length of its action in these periods is the measure of the 115 amount of external work done.

In some cases where I may use a secondary condensing turbine in place of a regenerator to absorb the balance of available heat in the exhaust gases from the main 120 turbine I use this to drive the compressor. In some cases this may be supplemented by a self-governing turbine of the air-steam type which will give the balance of power and effect the necessary regulation. This 125 method of driving is also applicable to compressors other than those of the type which I have mentioned.

In order to obtain the best results with the cycles used in connection with the appa- 130

ratus and under conditions of service which I have laid down, it is necessary to always use a regenerator or reëvaporator. The regenerator may be made and applied so as to take out and utilize the heat from the exhaust gases.

Where a turbine using a mixture of superheated steam and air is provided and water for condensing is available, I may then employ a secondary turbine to use the balance of heat in the exhaust, and as already explained, may employ this for driving a compressor, or for assisting the main turbine in one direction, or for driving any auxiliary machinery. This turbine may be of the pressure flow type, and is the only case in this specification where the turbines spoken of are of this type.

In order to satisfactorily carry my invention into effect, it is necessary that the turbine should be so constructed that they should be capable of easily varying the number of times the working fluid is passed through the blades, so as to get easy and efficient speed variation with a constant velocity of working fluid. I can best accomplish this by means of two impact wheels, such as the Laval, placed in close proximity to each other and arranged to rotate in opposite directions. In some cases the fluid is delivered direct from one wheel into the next, and in others guide blades are used in between. Where, however, guide blades in between are used it is necessary to form them with a different receiving angle to the angle of delivery, although the blades are placed in the direction of flow of the working fluid, and only slightly diverting it from its natural course. This necessitates a certain thickness of the guide blades, so as to keep the correct area, which in its turn necessitates a division of the nozzle or stream from the nozzle so that shock against the central dividing blades may not be experienced.

I will now describe forms of turbines with oppositely running wheels adapted to extract from the fluid the high velocity imparted to it in its expansion in the nozzles.

According to one method I form these adjoining oppositely running impact wheels (see Fig. 4) with blades, v and w , of sufficient length radially to enable the working fluid to be first passed through at one radius and then to be curved around by means of the guide ducts, 3, and passed back again through the wheels in the opposite direction at another radius this operation being performed once or as many times as is necessary to get sufficient reactions at the speed of running to absorb the kinetic energy in the working fluid. According to this method I am able to give the guide ducts a different angle according to the progression of the working fluid through them, as

the working fluid always passes in the same direction through them at any one radius and therefore notwithstanding the variation of angle which should exist between the blades of the running wheels in the successive passes, a compromise is effected whereby the angle is approximately right for the several conditions at varying speeds. These returning guides on each side of the oppositely running wheels are of course correctly proportioned otherwise as regards, for example, sectional area.

According to another method, (see Fig. 5) I use two oppositely running wheels as above described but with the blades, v and w , of only sufficient radial depth for one passage of the fluid. I pass the fluid through both wheels at one radius and by means of suitable returning guides, 5, pass it back again at the same radius through the wheel and repeat this operation a sufficient number of times to take out the velocity of the working fluid. According to this method the working fluid travels through the blades in the opposite direction at each pass. With the turbine so constructed, and passing the working fluid from the nozzle through the first and second wheels, and by means of returning guides back again through the second and first wheel, I get equal power on each wheel. There is, however, more shock in passing from wheel to wheel according to this method than according to that before-described, as the fluid is passed through the wheel alternately backward and forward.

With either of the above arrangements as described I use the turbines described for marine purposes, one working on each of a pair of screws mounted on concentric shafts. The passage backward and forward of the working fluid through the blades allows the use of quite simple wheels, which may be made of considerable diameter, and thus a low speed obtained. Varying the number of passes in a manner to be described also gives the desired speed, according to these methods. In order, however, to make the arrangement complete in using turbines constructed according to Figs. 4 and 5, I require to place a turbine of any suitable type upon one or both of the concentric shafts for the purpose of running in the opposite direction for driving astern. These several turbines are started and stopped by means of a suitable gear, as described elsewhere in this specification so that the turbines may be worked to their full advantage. I, however, prefer to construct turbines which embody the reversing principle in their construction. I accomplish this according to one method (see Fig. 6) by making the blades, v and w , of three times the radial depth necessary for a single pass of the working fluid. Say this depth, for example, is one inch radially;

the blades are then made three inches long radially. Through the first inch, *i. e.*, the outermost one in the example shown, I pass the fluid from the nozzle, z , in one direction.

- 5 I then by means of suitable guides 3, return it through both wheels through the space occupied by the third or innermost inch of radial depth and so on backward and forward through the first and third inches of 10 radial depth the desired number of times. This part of the construction corresponds to that described with reference to Fig. 4. In the center inch of radial depth I form the blades pointing in the opposite direction 15 according to any well known methods and use this part of the blades for the purpose of reversing, *i. e.* running each wheel in the opposite direction to that arranged for running ahead when the nozzle, z , alone is 20 acting. I provide a reversing nozzle, z' , to co-act with the center inch of blades and in accordance with the method described with reference to Fig. 5, provide returning 25 guides such as 5.
- 25 According to another method, (see Figs. 7 and 8) I make the blades, v and w , of twice the radial depth necessary for one to pass and superpose two sets of blades and nozzles as shown. Thus for working in the ahead 30 direction the working fluid issuing from the nozzle, z , passes through the first inch of both wheels and is then returned for another pass through the guides, 5. Similarly for reversing, the fluid passes from the 35 reversing nozzle, z' , through the second inch of both wheels and is returned by the guides, 5^a.

I may employ any of the above constructions with guide blades in between oppositely running wheels, as indicated in several 40 of the drawings already described, and in this case I vary the angles of the guide blades, as regards their entering and leaving parts, for different positions around the 45 wheels according to the speed and number of reactions, thus getting the best results under all conditions. This variation of the angle of the guide blade is particularly applicable when for the purposes of speed and 50 power regulation, I divide the wheel into segments in a manner to be described. I, however, prefer in most cases simply to use the one wheel delivering into the next, making a compromise of the angles of entering 55 and leaving and correctly fixing the angles of the returning guides to the work they have to do.

In some cases I employ single wheels of 60 blades and pass the working fluid backward and forward through these blades by means of returning guides, such as already described, at a constant radius. This method, however, I only employ in connection with the turbines cut up into sections for varying 65 torque and speed in a manner to be described

the nozzles and return guides being arranged to suit these varying torques and speeds.

In the turbine shown in Fig. 9 two wheels, 20, and 21, are arranged co-axially, with the 70 blades, 22, 23, disposed in a direction parallel to the axis of the turbine, so that the fluid from the nozzle, z , after its first passage inwardly through the blades is returned by the guides, 26, for a second passage outwardly through a different part of the length of the blades, the process being repeated as 75 desirable.

So far in the foregoing description, where I have described turbines having oppositely 80 running wheels, each has been provided with a single set of blades. I may, however, vary these forms to the extent of employing multiple rings of blades, half of which are mounted on one wheel running 85 in one direction and the other half are mounted on a second wheel running in the opposite direction. Thus referring to Fig. 10, two rings of running blades, 27, are fixed radially to the broad rim of a single wheel, 28, the blades being thereby constrained to run in the same direction. In between these two rings of blades, 27, another ring of 90 blades, 29, is arranged, which is connected to an outer ring of blades, 30, by means of 95 an external connecting piece, 31, the two rings of blades, 29 and 30, being carried by another wheel, 32. The blades, 29 and 30, are disposed so as to produce rotation of 100 the wheel 32, to which they are secured in 105 an opposite direction to that given by the blades, 27, mounted on the wheel, 28. It will thus be seen that since the blades, 29 are mounted on the external connecting 110 piece, 31, and are supported thereby, the power which they give is transmitted through the connecting piece, 31, and down to the wheel, 32, through the body of the remaining blades, 30. This system may 115 work according to any of the methods I have described in this portion of the specification with reference to turbines having radially disposed blades, the object of the arrangement being to get greater power into the space than can be obtained with a single pair of oppositely running wheels. Thus the blades may be of only sufficient length for a single pass or they may be double, three times or four times the length, all as 120 and for the purposes fully described above.

For the sake of example, I have shown in Fig. 10, a reversing turbine with blades double the length required for a single pass. For the ahead direction of rotation of the turbine, the nozzle, z , the outer length of 125 the running blades and the return guides, 33, are employed; for rotation in the opposite direction, the reversing nozzle, z' , the inner length of the running blades and the return guides, 34. The working fluid thus 130

receives four reversals in a single passage through the blades; by returning it once, it will then have received eight reversals and so on.

5 For the purpose of regulation, I construct turbines with the casing and its parts divided up into segments, and in these segments respectively, I provide such nozzles, guides and the like as are necessary to give 10 the different conditions of running I require. Thus, as indicated diagrammatically in Fig. 11, I divide the casing of a turbine of a non-reversing single wheel type into three segments, A, B and C, which are used respectively 15 for low, medium and high speeds. In sections A, I arrange a nozzle, z , and one return guide, 34, thus securing two reactions on the wheel, 35; this is shown in Fig. 12. In section B, as shown in Fig. 13, the arrangement 20 is similar but I use three return guides thereby securing four reactions on the wheel and finally in section C, as shown in Fig. 14, I provide four return guides, 34, giving five reactions on the wheel. The 25 essence of this part of my invention is that by providing a separate set of nozzles and return guides for each speed, I am able to give correct angles to the guides in the different segments, which would be impossible 30 if I merely varied the number of passes through the blades using as many as required of one set of return guides.

It will be obvious that in order to vary 35 the power at any of the pre-arranged speeds I may provide a plurality of each or any of the arrangements shown in Figs. 12 to 14 respectively in the corresponding segment of the turbine.

In applying my invention to a reversing 40 turbine of the type described with reference to Fig. 6, having provision for three efficient speeds ahead and one astern and referring to Fig. 15, an end elevation of the turbine is shown, the radial distances apart of 45 the four concentric circles, 36, representing the three lengths, each say of one inch, into which the blades are divided. The turbine it will be seen is divided into four segments, 50 A, B, C, and D. In segment A, which is used for full power and speed ahead, five nozzles, z , are provided and the fluid issuing from each is caused to make eight passes through the blades, this being effected by the return guides numbered 3 in Fig. 15^a 55 and diagrammatically indicated in Fig. 15 by the zigzag lines issuing from the respective nozzles; the numerals adjacent to these lines indicate the number of passes made by the fluid through the turbine at these points. 60 In segment, B, are arranged two nozzles, z , the fluid from each making ten passes Fig. 15^b through the blades; this segment is used for, say, .4 of the full power ahead and .8 of the speed. In segment, C, one nozzle is 65 arranged, the fluid making twelve passes

Fig. 15^c through the blades and giving say, .2 of the full power and .6 of the speed. The segments, A, B, and C, thus provide efficient means of procuring the three different ahead speeds. Finally in segment D, I 70 provide in the middle inch of the blades, five reversing nozzles, z' , the fluid from each making eight passes Fig. 15^d through the blades. These successive passes are not indicated in Fig. 15 to avoid confusion since they are all effected at the same radius. It will be seen that this arrangement provides for efficient working of the turbine at only one speed viz., full speed astern, but by shutting off one or more of the nozzles, z' , 80 other speeds may be secured but of course with diminished efficiencies. Similar remarks apply to segments, A and B. It will further be obvious that instead of providing a plurality of nozzles in each of the segments A, B, and C, I may provide single nozzles of different sizes but in most cases I prefer the arrangement above described.

In some cases the returning ducts may be worked into and out of position by means 90 of suitable relay gear connected with the control mechanism of the turbine. By means of a governor working by variation of speed of the turbine, I may vary automatically the number of returns through the 95 blades according to the speed at which the turbine is running. For example, the faster the turbine runs, the fewer the number of return blades that are required, and therefore the fewer the number of times the 100 working fluid is passed backward and forward. On the other hand, if the speed falls, the governor automatically puts into place additional reaction ducts which conduct the working fluid backward and forward a 105 greater number of times and so add to the torque capacity of the turbines at the particular speed. The power to be given out by the turbine at any one speed will then depend upon the number of nozzles and chambers that are thrown into action by the main control of the apparatus.

I may automatically control the number of reactions in accordance with the speed according to another method. For this purpose, (see Fig. 16), I pivot the reaction ducts or return guides, 37, by attaching to them a knife edge, 38, or the like resting in a corresponding recess or socket, 39. I so arrange the position of this pivot or hinge 115 device that the action of the working fluid passing through the guide exerts a force which tends to keep it in position close to the blades, 40, suitable stops or the like being provided as required to prevent actual 120 contact. This action I assist by means of a light spring, (such as 41 in a state of compression) or a counterweight suitably arranged to keep the guide in a working position. When the speed rises so that the dis-

charge of working fluid from any portion of the wheel ceases to be in the direction of the guides and takes place either at right angles to the plane of rotation or in advance 5 of this, there is then no longer any force save that of the spring or counterweight tending to keep the return ducts in close proximity to the blades and they are therefore blown back by the issuing working fluid 10 into some non-effective position such as that shown in Fig. 17, the number of reactions being thus automatically reduced. Directly this action ceases to take place, the returning ducts drop back into working position 15 alongside the running wheels, so as to make the maximum number of reactions. When the turbine is at rest the maximum number of reactions will be obtained at starting. These moving ducts may automatically adjust themselves to the power being developed 20 and thus produce more efficient working.

The number of nozzles in action may be varied so as to diminish the available horse power given to the wheel at the low speeds.

25 In some cases where I employ multiple outflow nozzles such as 50, (see Fig. 18), issuing directly from the combustion chamber, I provide a water jacket, 51, locally around parts of the nozzles and in some 30 cases between the individual nozzles likewise as shown. The signification of other reference symbols on this drawing has already been explained.

As before described, I preferably construct 35 the combustion chambers, *a*, in such a way that the combustion chamber proper is cooled by jacketing it with the air supply. The external shell, 52, (see Figs. 18 and 19) forming the outer wall of the jacket, *e*, 40 through which the air is supplied can be readily made to stand the full pressure. Again in some cases, (see Fig. 19) I provide a long tube, 53, on the end of the combustion chamber, *a*, supplying this tube with 45 air through an annulus, 54, which is in direct communication with the jacket, *e*, surrounding the combustion chamber proper. I also supply fuel through a central orifice, 55, so arranged that the combustible mixture passes along the tube, 53, at high velocity thus preventing back ignition; or in some cases the straight mixing tube, 53, may be replaced by a mixing tube, in the form of a coil. The combustion chambers may be 50 arranged radially to the axis of the wheel or with their axes in planes parallel to the axis of the wheel and at any suitable angle to the plane of rotation or in any other convenient and suitable position.

60 I have already described with reference to Figs. 2 and 3 one form of the combustion chamber which I prefer to use as applied to a turbine together with the governing gear rendering it capable of working under 65 the widely varying conditions involved in

the present invention. In order to make the arrangements effective, I prefer to use separately driven compressing plant for supplying the necessary air under pressure for either the air or steam superheated turbines. 70 In the latter case the air compressor may be driven from the secondary turbine, assisted if need be and for purposes of starting by a primary turbine suitably governed to give the right amount of air to the system. The 75 compressor for this purpose may be of the reciprocating type working with say three stages, and arranged to compress as nearly isothermally as possible. Where the turbines are worked by air and the products of combustion and the power required for compression is considerable the compressing must be performed wholly or in large measure by means of a rotary compressor using liquid as the medium of compression. This 80 compressor is driven by a separate air turbine, and may be governed by means of intermittent operation as already described in this specification. Separate air reservoirs with proper air governing arrangements are 85 provided, so that a constant supply and small storage of air is kept; the storage of air being also necessary for starting purposes. It is then possible to arrange the 90 screw operating turbines so that they can 95 be easily handled by means of suitable valves, and worked under conditions of maximum economy at the various speeds and torques required from them.

Where I desire to drive paddle boats which do not require such large powers as above contemplated, I still prefer to use the same class of turbine consisting of oppositely running wheels. I may attach large toothed gear wheels, 56, (see Fig. 20) to the shafts 100 of the paddles, 57, with two pinions, 58, gearing into each of these main wheels. On the ends of these pinion shafts, I fit worm wheels, 59, and into these are geared worms, 60, mounted on the shafts of the oppositely running wheels of the turbine, 61. The turbines may be of the variable speed and reversing type, as already described, and one complete turbine is then fitted to each 105 paddle wheel, as shown. This arrangement enables rotation in either direction to be effected on each wheel independently of the other and therefore gives the boat facility for handling the best together with good 110 economy under all conditions. It is obvious that many detailed variations of the application of the turbines which I have described may be made to the driving of paddle wheels.

According to another method (see Figs. 21 and 22) I drive paddles, 57, by means of gear wheels, 56, which when it is desired to operate the paddles separately I fix upon the two separate shafts each carrying a paddle 115 as in the form of drive described with refer- 120

ence to Fig. 20. I gear one or more turbines, 61, on to these main gear wheels actuating the paddles and make these turbines of the type in which the two motor wheels of blades 5 run in opposite direction. I also make them by preference reversing. The motor wheels driving one paddle wheel, may have their shafts provided with pinions, 62, gearing direct into the corresponding gear wheel, 56; 10 the motor wheels driving the other paddle wheel also have their shafts fitted with pinions, 63, but these latter in order to get the right direction of rotation drive the corresponding gear wheel, 56; through an idler 15 wheel, 64. According to this method I can either run ahead or astern.

I provide both the shafts carrying the paddles with brake wheels, 65, and brake shoes or clamps, 66 pivotally mounted at 20 67^x, (see particularly Fig. 22) so that I can hold either of the paddle wheels. It is then possible with the reversing turbines to run the other wheel either ahead or astern. In this way, although the operation of the 25 boat may ordinarily be by means of both paddles going ahead or astern, I am able to obtain additional control for turning in a circle of small radius or of other purposes of easy handling. The wheels when both 30 free also rotate at different speeds when the vessel is making a circle, and this facilitates the steering of the boat. In place of gearing through an idler wheel one of the main gear wheels may gear with an externally toothed, 35 spur wheel and the other with an internally toothed spur wheel provided that both sets are approximately the same ratio of gearing.

I wish it to be understood that although I have described my invention as applied to 40 ships, boats and the like, yet it is evident that it may be applied to other power installations in which it is necessary to vary the torque according to the power required, as in those cases where it is required to run 45 speeds other than the normal for considerable periods of time.

I wish it to be understood that where in the foregoing description and claims I have used the term internal combustion turbine, 50 I intend to include only those cases in which the energy derived from the combustion of the fuel is imparted to the working fluid previous to, or during its expansion in the fixed parts of the turbine and not on its 55 passage through the blades.

What I claim as my invention and desire to secure by Letters Patent is:—

1. In combination, a turbine having one or more bladed members, a plurality of 60 guides coacting with the blades of said members to form a plurality of paths for the working fluid of varying operative lengths, together with means for supplying working fluid to any of said paths at will.

65 2. In combination, a turbine having one

or more bladed members, a plurality of guides coacting with the blades of said members to form a plurality of paths for the working fluid of varying operative lengths, means for generating said working fluid, 70 means for heating said generated fluid by internal combustion, together with means for supplying said fluid to any of said paths at will.

3. In combination, a turbine having one 75 or more fluid members, a plurality of guides coacting with the blades of said members to form a plurality of paths for the working fluid of varying operative lengths, means for generating condensable elastic fluid, 80 means for heating said condensable elastic fluid, together with means for supplying said fluid to any of said paths at will.

4. In combination, a turbine having one 85 or more bladed members, a plurality of guides coacting with the blades of said members to form a plurality of paths for the working fluid of varying operative lengths, a source of elastic fluid under pressure, a 90 source of fuel, a combustion chamber in which said elastic fluid and fuel are burned, together with means for leading working fluid from said combustion chamber to any of said paths at will.

5. In combination, a turbine having one 95 or more bladed members, a plurality of guides coacting with the blades of said members to form a plurality of paths for the working fluid of varying operative lengths, a source of condensable elastic fluid under 100 pressure, a source of compressed air, a source of fuel, a combustion chamber in which fuel and air are burned to heat said condensable elastic fluid, together with means for leading the working fluid from said combustion chamber to any of said paths at will.

6. In combination, a turbine having one or more bladed members, a plurality of guides coacting with the blades of said members to form a plurality of paths for the working fluid of varying operative lengths, together with a second plurality of guides coacting with the blades of said members to form a second plurality of paths for the working fluid of varying operative lengths 110 for reversing the direction of rotation of the turbine.

7. In combination, a turbine having one or more bladed members, a plurality of guides coacting with the blades of said members to form a plurality of paths for the working fluid of varying operative lengths, a plurality of combustion chambers, means for introducing and igniting fuel and air in said combustion chambers, together with a plurality of nozzles coacting with said combustion chambers for leading working fluid to any of said paths at will.

8. In combination, a turbine having one or more bladed members rotating in oppo- 130

site directions, a plurality of guides coacting with the blades of said members to form a plurality of paths for the working fluid of varying operative lengths, together with 5 means for supplying working fluid to any of said paths at will.

In testimony whereof I have signed my

name to this specification in the presence of two subscribing witnesses.

SEBASTIAN ZIANI DE FERRANTI.
